COLLAPSIBLE IRONING TABLE

Chester A. Rich and Jesse W. Richardson, Cincinnati, Ohio, assignors, by direct and mesne assignments, to The Rich Pump & Ladder Company, Cincinnati, Ohio, a corporation of Ohio

Application December 4, 1933, Serial No. 700,802

7 Claims. (Cl. 68—10)

This invention relates to a collapsible ironing table, an object of the invention being to reduce to a minimum the cost of manufacturing such devices while at the same time rendering them very sturdy, durable, and easy to manipulate.

Other objects of the invention are: to provide a simplified construction with the use of inexpensive stock material, such as standard strap metal; to provide for automatic collapsing or 10 folding of the brace structure close against the under side of the board element; and to provide a rear trestle or leg structure which reduces its width automatically when the device is collapsed, with little or no assistance from the 15 front leg or brace assembly.

The foregoing and other objects are attained by the means described herein and disclosed in the accompanying drawings, in which:

Fig. 1 is a perspective view of the collapsible ironing table of the invention.

Fig. 2 is a plan view of a cross-member or brace employed in the device of the invention, and which forms part of a leg spreading assembly.

Fig. 3 is a rear elevational view of the rear 25 leg or trestle structure detached from the ironing board.

Fig. 4 is a fragmental side elevational view of a modified form of rear leg or trestle structure.

The board or table member 6 has a front or 30 forward end 7 and a rear end 8. Upon the under side of the board, adjacent to the rear end, is provided a suitable means for pivotally supporting the rear legs 9 and 10. Said means may be in the form of opposed perforated brackets 35 or lugs 12 which depend substantially vertically from the under side of the board. Any suitable means such as screws, rivets, or the like 13 may be employed to hold the brackets or lugs in place. The legs 9 and 10 are pivotally mounted upon the 40 lugs 12 as at 14.

The inner face of each leg may be tapered or beveled as indicated at 15 (Fig. 3), so that when the legs are extended or projected away from the board to the operative position of Fig. 1, the 45 lower ends of the legs may readily be spaced apart at a greater distance than when the legs are folded against the board.

A forward or front leg 16, which if desired 50 may be constituted of the two shafts or elements 17 and 18, has pivotal mounting means at 19 upon the under side of the board. When the front or third leg 16 is made in two parts, as illustrated in Fig. 1, the shaft members 17 and 18 preferably are joined at their lower or free ends by

means of one or more rivets, screws or other fastening devices 20.

Each of the members 17 and 18 is pivoted at 19 upon the bracket members 21, the latter being suitably secured to the under side of the board 5 by means of rivets, screws, or other fastening devices 22. The upper ends of members 17 and 18 are cut at such an angle, as indicated at 23, that when the members are moved to the extended position the face 23 may abut the under 10 face of the board 6. The contact of said angle faces 23 upon the under face of the board substantially limits the extent to which the front leg may move toward the rear legs 9 and 10. While there is some slight flexibility or resiliency 15 in the members 17 and 18, it is to be understood that substantially the indicated limitation of movement is controlled by the abutment at 23.

The lower or free ends of the front leg members have pivotally attached to them the forward 20 end of a substantially V-shaped connector or tension element 24 having the pair of arms 25 and 26. The apex or base part 25 is suitably pivoted upon the leg 16.

At the rear ends of the rods 25 and 26, suitable 25 abutment means or heads 27 and 28 are provided. Said heads are adapted to abut, respectively, the sleeves 29 and 30 through which the rods extend. The rods are slidable in the sleeves, and the sleeves are pivotally mounted relative to the rear legs as at 31 and 32. The pivotal mountings indicated at 31 and 32 may alternatively be carried by the braces or struts 33 and 34, as is evident from the drawings. From the foregoing it will be understood that the rods 35 25 and 26 function to maintain a predetermined spacing of the rear legs from the front leg when force is applied to the upper face of the board 6.

The braces or struts 33 and 34 have their lower 40 ends pivoted upon the rear legs 9 and 10, respectively, at points intermediate the upper and lower extremities of the legs; and preferably, though not necessarily, the pivots 31 and 32 may be employed for this purpose, as shown. The front or upper ends of the struts preferably 45 are associated with a suitable operating member 35, or equivalent means, for forcing the struts to the operative position of Fig. 1 wherein the rods 25 and 26 are tensioned or substantially tensioned between the legs 16, 9 and 10. Although other 50 forms of operating members may readily be substituted for that disclosed herein, I prefer to illustrate the one shown in the accompanying drawings as it corresponds with the operating member shown in the Rich and Richardson copending ap- 55

lication filed June 26, 1933, and bearing Serial Number 677,633.

The struts will be seen to form part of a toggle structure, due to the fact that their front or upper ends are pivoted upon a member such as 35 which is adapted to be moved past center when actuated. As shown, the upper ends 36 of the struts are connected by a transverse or base portion 39 of the U-shaped operating member 35.

10 The operating member comprises also the arms or links 37 and 38, and these as well as the struts are included in the toggle structure.

The free ends of the arms 37 and 38 are turned outwardly as indicated at 40 and 41, and the said ends are received in pockets or bearings 42 and 43, respectively, provided by suitable brackets 44 and 45 mounted in spaced relation upon the under side of the board 6. The pockets or bearings are elongated in the direction of the length of board 6, thereby permitting some longitudinal movement of the member 35 relative to the board 6. Each of the arms 37 and 38 is provided with an offset or abutment 46, the purpose of which will be explained presently.

25 The base portion 39 of operating member 35 is pivotally mounted upon the struts 33 and 34, as previously stated, and a suitable hand piece 47 which is disposed intermediate the struts, retains the forward ends of the struts in opposed relationship.

Associated with the operating member 35 is a second U-shaped member 48 which has eyes 49 formed at the ends of its arms 50 and 51, and the arms are slidably received in the eyes 49. The base or transverse portion 52 of member 48 is pivoted to the board by means of the brackets 53. The eyes 49 are adapted to engage the abutments 46 at and shortly before the time that the toggle device comprising the struts 33-34 and member 35 attain the positions that they assume in the fully extended or operative position of Fig. 1. The various elements of the assembly at the front end of the board are so related and proportioned that a snap action over dead center of the member 35 results when the ironing table is set up for use, to maintain the leg structure in a substantial and rigid condition. The reader is referred to the copending application of Rich and Richardson, previously referred to, for a more detailed explanation of the operation of the toggle structure.

Attention now is directed to the means for spreading the legs 9 and 10 laterally when the device is set up, and for bringing the legs toward each other when the device is collapsed so as to dispose the legs substantially within the body lines of the board 6. Said means comprises a pair of cross braces or spreaders 54 and 55, the lower ends of which are pivoted, respectively, upon the rear faces of the legs 9 and 10, as at 56 and 57, (Fig. 3). The braces are crossed, as shown, and the upper ends 58 and 59 are twisted and turned so as to lie substantially in planes perpendicular to the board. Each of the turned upper ends of the braces is perforated to receive rivets or the like 60 whereby said ends are pivoted upon pivot-carrying links or supports 61 and 62. The pivot-carrying links or members 61 and 62 are slidably received in sleeves or guides 63 and 64, respectively, and the latter are pivotally mounted for rotation upon the legs as at 65 and 66. The opposite ends of members 61 and 62 may be pivoted upon the front leg members as at 67 and 68, as in Fig. 1, or if desired, they may each be pivoted upon a stationary part of the device, as

indicated at 69, of the Fig. 4 modification. The members 61 and 62 preferably are disposed in substantial parallelism with the board, as indicated by Figs. 3 and 4.

The effect of the cross brace and link construction above described, is to render the rear leg spreading action practically independent of the front leg strut and tension assembly. In other words, the spreading action of the rear legs when manually moved toward and from the board, would be accomplished even in the absence of the struts 33-34, the rods 25-26, and the leg 16. The spreading action results from the slight shifting of pivots 60 toward the pivots 56-57 when the legs are moved to the extended position, and, conversely, the legs move toward each other when the pivots 60 are shifted upwardly or toward the rear leg pivots, upon folding of the legs toward the board. The shifting action of pivots 60 occurs in the Fig. 4 modification also, as is evident.

It is to be observed that all the metal parts of the device may be formed easily and inexpensively of stock strap material that may be cold pressed and shaped by means of simple press operations, thereby reducing the cost of manufacture to a minimum. Moreover, assembly costs are reduced by providing rear leg spreading means operating independently of the other elements, since such construction obviates much of the labor that would otherwise be required for co-ordinating the movements of the rear legs with those of such other elements.

What is claimed is:

1. A folding table structure comprising in combination a top board, rear legs pivoted to the board for movement toward and from the board to and from an extended operative position and a collapsed inoperative position, a cross brace having its lower end pivoted upon one of the rear legs at a point remote from the board, a link guide mounted upon the other leg adjacent to the pivotal mounting of the leg upon the board, a link supported by the guide, said link having opposite ends, a connection between one end of the link and the upper end of the cross brace, and means for mounting the other end of the link upon a stationary part of the table.

2. A folding table structure comprising in combination a top board, rear legs pivoted to said board for movement toward and from the board to and from an extended operative position and a collapsed inoperative position, a cross brace having opposite ends, the lower end being pivoted upon one of the rear legs at a point remote from the board, a link guide having a pivotal mounting upon the other leg adjacent to the pivotal mounting of the leg upon the board, the pivotal mounting of the link guide being substantially parallel with that of the leg, a link slidably supported by the guide in substantial parallelism with the board, with opposite ends of the link disposed at opposite sides of the guide, a pivotal mounting between one end of the link and the upper end of the cross brace, a depending member on the board remote from the rear legs, and means for mounting the opposite end of the link upon the depending member.

3. A folding table structure comprising in combination a top board, rear legs pivoted to said board for movement toward and from the board to and from an extended operative position and a collapsed inoperative position, a cross brace having opposite ends, the lower end being pivoted upon one of the rear legs at a point remote from

- the board, a link guide having a pivotal mounting upon the other leg adjacent to the pivotal mounting of the leg upon the board, the pivotal mounting of the link guide being substantially 5 parallel with that of the leg, a link slidably supported by the guide in substantial parallelism with the board, with opposite ends of the link disposed at opposite sides of the guide, a pivotal mounting between one end of the link and the 10 upper end of the cross brace, a front leg movably mounted upon the board remote from the rear legs, and means for mounting the opposite end of the link upon the front leg.
4. A folding table structure comprising in combination a top board, rear legs pivoted to said board for movement toward and from the board to and from an extended operative position and a collapsed inoperative position, a cross brace having opposite ends, the lower end being pivoted upon one of the rear legs at a point remote 15 from the board, a link guide mounted upon the other leg adjacent to the pivotal mounting of the leg upon the board, a link slidably supported by the guide, with opposite ends of the link disposed at opposite sides of the guide, a pivotal mounting between one end of the link and the upper end of the cross brace, a pivot supporting means depending from the board remote from the rear legs, and means for mounting the opposite end 20 of the link upon the pivot supporting means.
5. A folding table structure comprising in combination a top board, rear legs pivoted near the rear of said board for movement toward and from the board to and from an extended operative position and a collapsed inoperative position, a front leg structure pivoted upon the board forwardly of the rear leg pivots for movement toward and from the front end of the board, means for limiting movement of the front leg structure away from the front end of the board to an extended operative position, means for maintaining 25 the front leg structure and the rear legs in extended operative position, a cross brace having 30 opposite ends, the lower end thereof being mounted upon one of the rear legs at a point remote from the board, a link shiftable relatively to the other rear leg, a pivot on one end of the link and shiftable therewith, a connection between the shiftable pivot and the upper end of the cross brace, and means for shifting the link and the pivot carried thereby when the legs are moved to the inoperative position.
6. A folding table structure comprising in combination a top board having a front and a rear end, rear legs pivoted to said board near the rear end thereof and front legs pivoted to said board forwardly of and remote from the rear legs, for movement toward and from an extended operative 35 position and a collapsed inoperative position, the rear legs each having a rear face, a cross brace having one end pivoted upon one rear leg in the plane of the rear face thereof, at a location remote from the board, a pivot means on the other end of the cross brace adjacent to the pivotal mounting of the other rear leg, and means comprising a link operated by a front leg to shift the said pivot means on said other end of the cross brace, thereby increasing the angle 40 between the rear legs when said legs are extended.
7. A folding table structure comprising in combination a top board, rear legs pivoted to the board for movement toward and from the board to and from an extended operative position and a collapsed inoperative position, front legs pivoted to said board forwardly of the rear legs, a cross brace having its lower end pivoted upon one of the rear legs at a point remote from the board, a link guide mounted upon the other leg adjacent 45 to the pivotal mounting of the leg upon the board, a link supported by the guide, said link having opposite ends, a connection between one end of the link and the other end of the cross brace, and means for mounting the other end of the link 50 upon the front leg.
